UNITED STATES PATENT OFFICE.

ALBERT W. P. VERGEER, OF NEW YORK, N. Y., ASSIGNOR TO THE T. F. MOORE COMPANY, INC., OF NEW YORK, N. Y., A CORPORATION OF NEW YORK.

DISPLAY-STAND.

1,359,937.

Specification of Letters Patent. Patented Nov. 23, 1920.

Application filed April 3, 1918. Serial No. 226,354.

To all whom it may concern:

Be it known that I, ALBERT W. P. VERGEER, a citizen of the United States, residing at New York city, in the county of 5 Kings and State of New York, have invented certain new and useful Improvements in Display-Stands, fully described and represented in the following specification and the accompanying drawings, forming a part of the same.

This invention relates to collapsible display stands, and more particularly to such stands for displaying shoes, slippers and the like. The invention aims to provide a display stand of simple and cheap construction which may be readily opened or set up and folded or collapsed, and which when set up will afford an attractive and firm support for the shoe or other article to be displayed.

20 The invention consists in the features of construction, arrangement and combination of parts hereinafter described and specifically set forth in the claims.

An understanding of the invention can best be given by a detailed description of an approved form of display stand embodying the same, and such a description will now be given in connection with the accompanying drawings showing such a display stand 30 which embodies the features of the invention in the form which I now consider best. In said drawings:

Figure 1 is a view in front elevation of the display stand in open or set-up condition;

Fig. 2 is a view in side elevation; and

Fig. 3 is a rear view of the stand in folded or collapsed condition.

Referring to the drawings, the display stand illustrated comprises a flat rest 1, and a support formed by a front member 2 and a rear member 3 which when the stand is set up extends at right angles to the member 2. Said parts are desirably made of suitable sheet material such as stiff cardboard. The rest 1 is hinged on a line intermediate the ends thereof to the upper end of the front support member 2 so as to permit the rest to take a position such as shown in Figs. 1 and 2, or to be folded to bring its lower portion flat against the front face of the member 2 as shown in Fig. 3. The hinge connection between the rest 1 and the member 2 is, when the parts are made of cardboard, conveniently formed by shaping the member

2 with a hinge piece 4 extending beyond a score line at the upper end of said member and gluing or otherwise securing such hinge piece to the under side of the rest 1. The upper edge of the member 3 is shaped to serve as a support for the upper or rear portion of the rest when the stand is set up, such edge extending most desirably at such an angle to the bottom edge of the member as to support the rest in an inclined position 65 as shown in Fig. 2.

The rear member 3 of the support has a hinge connection to the rear side of the front member 2, conveniently provided when the parts are made of cardboard by a hinge 70 piece 5 which extends from the front edge of the body portion of the member 3, the member being suitably scored on the hinge line, and which hinge piece is glued or otherwise secured to the rear face of the front member 2 in position to locate the hinge line approximately in the longitudinal center line of the member 2. In order to support the lower portion of the rest when the stand is set up, the member 3 is provided 80 with a strut 6 projecting from its forward edge through an opening in the front member 2 and having an edge in alinement with the upper edge of the main portion of the member 3. Both the front and rear portions 85 of the rest 1 will thus be directly supported when the stand is set up, and the inclination of the rest will depend upon the angle of the alined edges of the strut 6 and upper end of the member 3 to the bottom edge of the member 3. The bottom edge of the member 3 desirably extends at an angle to the front 90 edge thereof which is slightly less than a right angle so that the front member 2 will be inclined slightly backward from the vertical.

For holding the rear support member 3 in position at right angles to the front member 2 when the stand is set up, and for holding the rest 1 down in engagement with the upper edge of the member 3, as well as to provide means for retaining the shoe or other article in position on the inclined rest 1, the top edge of the member 3 is shaped with a projection 7 and the rest has an opening 8 100 formed therein in position to receive the projection 7 when the parts are in set-up position. The opening 8 is made to receive the projection 7 with a tight fit so as to have sufficient frictional hold on the projection 110

to cause the rest to be firmly held down against the edge of the member 3. The projection 7, extending above the upper surface of the rest 1 when the stand is set up, serves as a means for engaging the front of the heel of a shoe placed on the stand to hold the shoe against sliding downward on the rest. The member 3 may also desirably be provided with a hinge piece 9 cut out from the body of the member adjacent its hinge edge, which when the stand is set up may be turned outward to bear against the rear side of the member 2 and serve as an additional means for holding the member 3 in position at right angles to the member 2. When folded back to lie in the plane of the member 3, this hinge piece will offer no hindrance to the folding of the member 3 flat against the member 2.

20 When the stand is collapsed the parts lie folded flat against each other as shown by Fig. 3. To set the stand up for use, the rear support member 3 is turned to a position at right angles to the front member 2 and the rest 1 is swung into the position shown in Figs. 1 and 2 and the projection 7 is passed through the opening 8 in the rest and the piece 9 is turned down to bear against the side of the member 2. To collapse the stand, 30 it is only necessary to disengage the projection 7 from the rest and turn the piece 9 back to the plane of the member 3 and then fold the parts flatwise together.

The stand shown is especially intended for 35 use as a shoe display stand, but stands may be made according to the invention for various purposes and of various shapes and proportions as may be desired. The front member 2 of the support in the stand shown 40 serves as an advertising or display card, its front surface being provided with such printing or display matter as may be desired.

What is claimed is:

45 1. A collapsible display stand, comprising a front support member, a rest for the article to be displayed hinged to said support member, and a rear support member connected to the rear side of the front support member and provided with a part extending through the front support member to engage the under side of said rest to support the same in operative position, said rear support member being movable to permit

the rest to be folded flat against the front 55 support member.

2. A collapsible display stand, comprising a front support member, a rest for the article to be displayed hinged at a point intermediate its ends to the upper edge of said support member, and a rear support member hinged to said front support member and adapted to extend rearward therefrom when the stand is set up, the upper edge of said rear support member being formed to support the rear portion of said rest when the stand is set up and said rear member having a part extending forward of the front support member to support the front portion of said rest.

3. A collapsible display stand, comprising a support member formed of sheet material and serving as a display card, a rest for the article to be displayed formed of sheet material hinged at a point intermediate its 75 ends to the upper edge of said support member, and a second support member hinged to the first said support member and formed to hold the rest in position by engagement with the under side thereof on both sides of the first said support member when the stand is set up, the second said support member being provided with a projection to cooperate with the rear portion of the rest to detachably connect said member and the rest 80 in set-up position and projecting above the rest to serve as means for holding the article 85 to be displayed in position on the rest.

4. A collapsible display stand, comprising a support member formed of sheet material 90 and serving as a display card, a rest for the article to be displayed formed of sheet material hinged at a point intermediate its ends to the upper edge of said support member, and a second support member hinged to the 95 first said support member and formed to hold the rest in position by engagement with the underside thereof on both sides of the first said support member when the stand is set up.

In testimony whereof I have hereunto set my hand in the presence of two subscribing witnesses.

ALBERT W. P. VERGEER.
